UNITED STATES PATENT OFFICE.

GLENN T. WILLIS, OF FRESNO, CALIFORNIA, ASSIGNOR TO JAMES PORTEOUS, OF SAME PLACE.

DESIGN FOR A FINGER-GUARD BAR FOR HEADERS AND HARVESTERS.

SPECIFICATION forming part of Design No. 38,475, dated October 30, 1900.

Application filed September 5, 1900. Serial No. 29,091. Term of patent 14 years.

To all whom it may concern:

Be it known that I, GLENN T. WILLIS, a citizen of the United States, residing at Fresno, county of Fresno, State of California, have 5 invented and produced a new and original Design for a Finger-Guard Bar for Headers and Harvesters, of which the following is a specification, reference being had to the accompanying drawings, forming part thereof.

10 Figure 1 is a perspective view of a finger-guard bar, showing my new design. Fig. 2 is an end view of same.

The material feature of my design is the substantially upright bar or plate A, having 15 the forwardly curved top B, the substantially

horizontal shelf C, projecting from its back below its top, and the thickened portion D on its back below said shelf.

Having thus described my invention, what I claim as new, and desire to secure by Letters 20 Patent, is—

The design for a finger-guard bar for headers and harvesters, substantially as herein shown and described.

In witness whereof I have hereunto set my 25 hand.

GLENN T. WILLIS.
